ATTORNEY

UNITED STATES PATENT OFFICE.

EDMUND R. BARANY, OF BROOKLYN, NEW YORK, ASSIGNOR TO FRENCH BATTERY COMPANY, OF MADISON, WISCONSIN, A CORPORATION OF WISCONSIN.

ELECTRICAL HANDLAMP.

Application filed January 31, 1925. Serial No. 5,943.

This invention relates to a combination switching and focusing device for electrical hand lamps.

A general object of the invention is to provide in a lamp construction of the type referred to, switch actuating means and lamp focusing means so disposed as to be conveniently operated by one hand of the user.

The invention includes a lamp supporting bracket having a slidable connection with its support and provided with an actuating member in the form of a slidable thumb piece accessible at the surface of the lamp casing. A spring contact member is arranged to constantly engage one of the lamp contacts in any position of adjustment in which the lamp may be placed. A switch member having an actuating button or handle placed closely adjacent the actuating member for the focusing device is arranged to close or open a circuit through the spring contact member to the lamp and is arranged to automatically remain in either its closed or opened position.

Other features of the invention will be hereinafter referred to.

In the drawings, in which a preferred embodiment of the invention has been selected for illustration,

Figure 1 is a view in longitudinal section of an electrical hand lamp equipped with switching and focusing devices embodying the invention.

Figure 2 is a view in transverse section taken on the line 2—2 of Figure 1.

Figure 3 is a sectional detail view taken on the line 3—3 of Figure 2.

Figure 4 is a sectional view taken on the line 4—4 of Figure 1.

Figure 5 is a sectional detail view taken on the line 5—5 of Figure 2.

Figure 6 is a view in cross-section taken on the line 6—6 of Figure 5.

Referring to the drawings for a more detailed description of the invention, in Figure 1 there is shown a hand lamp construction including a tubular casing 10 which serves as a handle member and as a receptacle for a battery cell 11. The forward extremity of the tubular casing 10 is provided with a screw-threaded section 12 for engagement with an annular member 13 for supporting an outwardly extending flange member 14 on a reflector 15. A lens 16 rests on the reflector flange 14 and is held in place thereon by a bezel or ring 16' which has a screw-threaded

connection at 13' with the outer surface of the ring-shaped reflector-supporting member 13.

The rearward extremity of the reflector 15 is provided with an opening 15' through which a lamp receiving socket 17 extends 60 and with which the plug 18 of the lamp 19 has screw-threaded engagement. The opening 15' in the reflector 15 has a diameter such that the lamp receiving socket 17 may pass freely therethrough without contact with the reflector in order to provide for focusing adjustment of the lamp 19 along the axis of the reflector 15.

At a point spaced to the rear of the reflector 15 is a septum or partition 20 formed 70 of insulating material and seated at its edges in a groove 21 formed in the inner wall of the casing member 10. The septum or frame member 20 provides a support for the lamp supporting devices as well as for switch 75 mechanism and focusing devices hereinafter referred to. The septum 20 is held in place in the seating groove 21 by means of a pair of strut members 22 attached at their lower ends to the septum 20 and provided with shoulders 80

23 near their upper ends which are adapted to engage beneath a pair of inturned lugs or flange members 24 formed on the edge of the casing 10. In order to remove the frame member 20 and the parts supported thereby 85 from its position in the seating groove 21, the extremities 25, of the strut members 22 are pressed inwardly toward each other and out of engaging position with the locking lugs 24 whereupon the frame member 20 may be 90 freely removed through the open end of the casing 10.

The lamp receiving socket 17 is supported by a bracket member 26 which is in turn slidably mounted in a guideway 27 carried by the frame member 20. The bracket member 26 is provided with a thumb piece 28 which projects outwardly through the side wall of the casing 10 in a position accessible to the thumb of the user. The thumb member 28 is movable in a slot 29 in the casing 10 and operates through slits formed for the purpose in the guide member 27. By this arrangement and construction, movement of the thumb piece 28 longitudinally of the casing 10 provides 105 for the corresponding adjustment of the lamp 19 carried by the bracket 26 along the axis of the reflecting member 15.

In order to control the operation of the lamp 19 by making or breaking a circuit 110

therethrough, a spring contact member 30 is mounted on the frame member 20 and engages the downwardly projecting contact 31 formed on the inner end of the lamp plug 18, 5 the spring contact 30 operating to maintain engagement with the contact 31 in all the adjusted positions into which the lamp 19 may be placed. A downward extension 32 of the spring contact member 30 occupies a position such that a switch member 33 pivotally 10 mounted at 34 on a bracket 35 can be moved into engagement with the spring contact 32 when an actuating button or handle 36 is moved from the full-line to the dotted-line 15 position shown in Figure 1 of the drawings. The bracket member 35 on which the switch member 33 is mounted, is carried by the frame member 20 and is at all times in contacting engagement with the center contact 20 37 of the battery cell 11 so that engagement of the switch member with the contact 32 completes a circuit through the lamp 19 as follows: outer pole of battery cell 11, slideway 27, bracket 26, socket 17, lamp contact 25 18, filament 38, lamp contact 31, spring contact 30, spring contact 32, switch member 33 and bracket member 35 to contact 37 of battery cell 11. It is usual, in electric hand 30 lamps of this class, to establish electric connection between the zinc cup of the dry cell and the casing of the hand lamp, the casing thus serving as a portion of the circuit. In the present instance, the circuit is completed from the casing to the member 26, as illustrated in Fig. 5.

In order to hold the switch member 33 in either its circuit closing or circuit opening position, a spring member 39 is provided which engages with flat surfaces 40 and 41 40 formed on the edge of the switch member 33 to hold the switch member in either one of its operative positions.

In order to facilitate the operation of the switch member 33 and the focusing bracket 45 26 by the thumb of the same hand of the user, the operating member 28 of the focusing device and the operating member 36 of the switch device are placed in close proximity to each other as is indicated in Figure 2 50 of the drawing. By this arrangement the operation of both the switching device and the focusing device can be achieved without the use of both hands of the operator, thereby leaving the other hand free and completely 55 controlling the lamp by the hand in which it is held.

Inasmuch as many changes could be made in the above construction, and many apparently widely different embodiments of my 60 invention could be made without departing from the scope thereof, it is intended that all matter contained in the above description or shown in the accompanying drawings shall be interpreted as illustrative and not in a limiting sense.

It is also to be understood that the language used in the following claims is intended to cover all the generic and specific features of the invention herein described and all statements of the scope of the invention which, as a matter of language, might be said to fall therebetween.

What is claimed is:—

1. In an electrical hand lamp, a reflector at one end of the lamp casing and a lamp 75 mounted in the rearmost part of the reflector, a transversely extending frame member formed of insulating material and spaced to the rear of the reflector, a spring contact member supported by the frame member and engaging a contact of the lamp, said spring contact member extending also to the rear of the frame member, a bracket formed of conducting material and supported by the frame member for contacting engagement 80 with a contact on the battery, a switch member pivotally mounted on the bracket for movement into or out of engagement with the spring contact member, and a spring for holding the switch in either of its operating positions.

2. In an electrical hand lamp, a reflector at one end of the lamp casing provided with an opening in the rearmost portion thereof, a transversely extending partition member 95 formed of insulating material and removably mounted in the casing at a position to the rear of the reflector, a lamp-supporting bracket member slidably supported on said partition member, a thumb-piece carried by said bracket member and extending through the side of the casing whereby to adjust the position of the lamp, a spring contact member carried by said partition member and engaging at one end with a contact on said lamp, a switch member carried by said partition member and having electrical communication with a contact of the battery, the switch member being movable to engage the other end of the spring contact member, and a thumb-piece for said switch member located in the casing wall adjacent the thumb-piece for operating the lamp focusing device.

3. In an electrical hand lamp, a reflector at one end of the lamp casing provided with an opening in the rearmost portion thereof, a transversely extending partition member formed of insulating material and removably mounted in the casing at a position to the rear of the reflector, a lamp-supporting bracket member slidably supported on said partition member, and a thumb-piece carried by the bracket member and extending through the side wall of the casing, whereby to adjust the lamp in said opening along 110 the axis of the reflector.

4. In an electric hand lamp, a reflector provided with an opening in the rearmost portion thereof, a partition within the casing to the rear of the reflector, a lamp supporting 115 120 125 130

bracket slidably supported on said partition, a thumb-piece carried by said bracket and extending through the side of the casing for adjusting the lamp, a spring contact member 5 carried by said partition member and engaging at one end with a contact on said lamp, a switch member carried by said partition member and having electrical communication with a contact of the battery, the switch 10 member being movable to engage the other end of the spring contact member, and a thumb-piece for said switch member located in the casing wall adjacent the thumb-piece for operating the lamp focusing device.

15 5. An electric hand lamp comprising a casing having one end equipped with a removable reflector, a dry cell in said casing, a lamp having a shank extending through said reflector, a partition member removably 20 secured in said casing between said reflector and dry cell and equipped with a spacing-member engaging said dry cell, a switch pivotally mounted on said spacing member and having a thumb piece projecting laterally through a slot in said casing, and resilient 25 means carried by said partition member and

co-acting with said switch to establish electric connection from the central pole of said dry cell to the central terminal of said lamp.

6. An electric hand lamp comprising a 30 casing having one end equipped with a removable reflector having a central opening, a partition member removably secured in said casing and equipped with a guide, a lamp supporting-member slidably mounted in said 35 guide and equipped with a thumb piece projecting through a slot in said casing, a lamp mounted in said support, a dry cell in said casing, a spacing-member secured to said partition member and engaging the central 40 pole of said dry cell, a switch mounted on said spacing-member and having a thumb piece working in a slot in said casing, and resilient means carried by said partition member and co-acting with said switch to 45 establish electric connection from the central pole of said dry cell to the central terminal of said lamp, said slide being in electrical connection with said casing.

In testimony whereof I affix my signature.

EDMUND R. BARANY.
